APPARATUS FOR CONTROLLING SELE-
TIVE DELIVERY OF FLUID FROM A CON-
TINUOUS DELIVERY SOURCE TO A FLUID-
DRIVEN MOTORJoseph F. Ziskal, Cicero, and William O. Bech-
man, Chicago, Ill., assignors to International
Harvester Company, a corporation of New
Jersey

Application July 18, 1945, Serial No. 605,706

6 Claims. (Cl. 60—52)

1

This invention concerns fluid-pressure operated power transmission systems utilizing fluid from a constant delivery source and operable to condition said source to develop relatively high pressure delivery only during periods of demand attendant to transmitting power. The invention has to do more particularly with fluid-energized control means employed with said systems.

The general object of this invention is the provision in a hydraulic power transmission system wherein there is a constant delivery source of motor-actuating fluid conditionable to deliver at relatively high and low pressures, of fluid-energized control means including valves selectively operable to direct the source output, and fluid motor means for selectively incurring operation of said valves concurrently with incurring conditioning of said source for high pressure and for incurring conditioning of said source for low pressure when none of the valves is operated.

A further contemplation and object of this invention is the provision in said fluid-energized control means of settable valve means having a portion manually settable in opposite directions from a neutral position relatively to a mechanically movable portion to cause operation of the valves to direct the fluid into a motor for causing corresponding directional operation thereof, and an operative drive connection between the motor and the mechanically movable valve portion for moving the same to reestablish said neutral position when the motor operates an amount and direction correlated with the amount and direction of setting of the manually settable portion.

A more thorough understanding of the invention and of the above and ancillary objects thereof can be had from the following description and the annexed drawings, wherein:

Figure 1 is a view partly diagrammatic illustrating a hydraulic power transmission system having a preferred form of the invention embodied therein.

Figure 2 is a side elevational view of a settable valve structure illustrated in the upper left-hand portion of Figure 1.

Figures 3, 4, 5 and 6 are respective sectional views taken transversely on the settable valve structure and taken on the lines 3—3, 4—4, 5—5 and 6—6 of Figure 2.

Figure 7 is a diagrammatic view illustrating a modified control valve means and by-pass-valve arrangement employable in the system of Figure 1.

The apparatus is for controlling delivery of propelling fluid from a source in the form of a pump P selectively to a motor M for causing movement of its piston 10 within a cylinder 11. Fluid is received into the pump P from a reservoir R through a conduit 12 and a master control for determining the pressure at which the

2

pump delivers fluid and for determining which end of the motor cylinder 11 receives the fluid and which end exhausts fluid is in the form of a settable valve structure 13 in the upper left-hand portion of Figure 1.

The assembled valve structure 13 comprises relatively movable parts 14 and 15 of which the former is a sleeve-like member journaled upon its outer cylindrical periphery within a casing 16. A sealing contact exists between the outer periphery of the rotatable sleeve 14 and the inner periphery of the casing 16 in contact therewith. A pair of diametrically opposite ports 17 and 18 of circumferential extent, illustrated in Figure 3, are formed in an upper portion of the sleeve 14. Grooves 19 and 21 extending circumferentially of the sleeve from the ports 17 and 18 are arranged diametrically opposite for contributing to a balance of fluid pressure between this sleeve and the casing to alleviate any tendency for disalignment or binding of the sleeve upon the casing when rotated relatively thereto. A second pair of diametrically opposite ports, 22 and 23, shown in Figure 4, are formed in the sleeve 14 below the ports 17 and 18. A third set of ports at a section below the ports 22 and 23 are designated 24 and 25 and are shown in Figures 2 and 5. A fourth set of diametrically opposite ports at a section below the ports 24 and 25 are designated 26 and 27 in Figure 6. Extensions 28 and 29, of the ports 26 and 27, formed similarly to the port extensions 19 and 21 appear in Figures 1 and 6.

At the outer periphery of the sleeve 14, the paired ports 17—18, 22—23, 24—25, and 26—27, respectively, cooperate with paired casing ports 31—32, 33—34, 35—36 and 37—38. At the inner periphery of the sleeve 14 the paired ports 17—18, 22—23, 24—25 and 26—27, respectively, cooperate with channels 41, 42, 43 and 44 bridging the rotatable core 15. The outer periphery of the core 15 has a slidable sealing contact with the inner periphery of the sleeve 14. Rotation of the core 15 is had by means of a handle 45. Rotation of the sleeve 14 is effected mechanically through a linkage comprising an arm 46 connected with the lower end of said sleeve and constrained for rotation therewith and a link 47 connecting an end of this arm with the outer end of a piston rod 48 of the piston or work member 10 of the motor M. Fluid is delivered to the motor M through a fluid conducting passage 49. This passage connects with one end of the cylinder 11 through an inlet passage X1 and connects with the opposite end of the cylinder through an inlet passage X2. Inlet passage X1 has an admittance valve X3 in series therewith and also a check valve X4. Passage X2 has an admittance valve X5 and a check valve X6. Exhaust passages X7 and X8 having exhaust valves X9 and 51 therein are communicative with opposite ends of the cylinder through

portions of the inlet passages **X1** and **X2**. Exhaust passages **X7** and **X8** are confluent with a passage **52** which leads to the reservoir. The associated valves **X3**, **X4** and **X9** control the admittance, exhaust and entrapment of fluid in the left end of the motor cylinder, while the associated valves **X5**, **X6** and **51** control the admittance, exhaust and entrapment of fluid in the opposite end of said cylinder.

Fluid motor units **53** and **54** operate the admittance valves **X3** and **X5**, whereas fluid motor units **55** and **56** operate the exhaust valves **X9** and **51**. Each of these motor units comprises a cylinder **CY** containing a piston **P1** from which a valve operating system **ST** extends downwardly for unseating the ball **B** of its associated normally closed valve. Branches of a conduit **57** are connected with the cylinders of motor units **53** and **56** for subjecting these motor units to a different status of fluid pressure to respectively incur the open position of the valves controlled thereby and their closed position. Branches of a conduit **58** are connected with motor units **54** and **55** to likewise subject these motor units to different pressures of operating fluid for incurring the same result.

With the parts in the condition illustrated in Figure 1, fluid discharged from the source **P** passes upwardly through a conduit **59**, past a by-pass valve having a valve seat **61** and a member **62** projectible into the seat for closing such valve. While the valve **61**—**62** is open, as shown, the fluid enters the reservoir **R** at low pressure through a by-pass passage **63** and the passage **64**. Some of the fluid diverts from the passage **59** through a fluid receiving passage **65** having a restricted flow capacity section **66**. Said fluid receiving passage has serially arranged openings in valve seats **67** and **68** which are adapted to be closed by cooperative valve members **69** and **71**. When the valve members **69** and **71** are elevated from their valve seats, as shown in Figure 1, fluid introduced into the fluid receiving passage **65** escapes at low pressure through the conduit **64** into the reservoir. Valve members **69** and **71** have pistons **72** and **73** upon their upper ends comprising the movable elements of fluid motor units **74** and **75**. The lower ends in these motor units are communicative with the source through conduits **76** and **77**, whereby fluid acting upon the lower ends of the pistons **72** and **73** can maintain these pistons at their upper limits of movement and thereby maintain the control valves **67**—**69** and **68**—**71** open.

The flow rate from the fluid receiving passage **65** through the open control valves **67**—**69** and **68**—**71** exceeds the flow capacity of the passage restricted section **66**, so that insufficient pressure of the fluid can build up in the passage **65** for forcing the fluid upwardly through a passage **78** into a chamber **79**, in which the by-pass valve member **62** slides, for supplementing a spring **81** in closing the by-pass valve. However, upon the closing of either of the control valves **67**—**69** or **68**—**71**, the pressure in the fluid receiving passage **65** will be increased with the effect of closing the by-pass valve and thereby conditioning the source **P** to deliver fluid at high pressure.

The relatively movable parts **14** and **15** of the assembled valve structure **13** are illustrated in their neutral position in Figures 1, 3, 4, 5 and 6. Manual movement of the handle **45** for rotating the core **15** in the counterclockwise direction relatively to the sleeve **14**, as viewed in Figures 3 to 6, will cause the apparatus to function for moving

the motor piston **10** to the left, whereas relative movement of the core **15** clockwise from the neutral position will incur movement of the motor piston to the right. Considering first the condition prevailing when the core and sleeve are in their neutral position, illustrated in Figures 3 to 6, each of the two core passages **41** and **44** register at their ends with the ports **17**—**18** and **26**—**27**. Ports **17**—**18** communicate through casing ports **31** and **32** with a branch of the conduit **58** and a branch of a conduit **85** which leads to the reservoir. Sleeve ports **26** and **27** communicate through their extensions **28** and **29** and valve casing ports **38** and **37** with a branch of the conduit **57** and a branch of said conduit **85**. Concurrently, the diametric channels **42** and **43** in the rotatable core **15** are blocked at their ends by the rotatable sleeve **14**, cutting off communication between the fluid conducting passage **49** and each of the conduits **57** and **58**. Therefore the conduits **57** and **58** are at this time connected communicatively with the reservoir through the valve structure **13** to permit exhaust of fluid from the motor units **53**, **55**, **56** and **54** by upward movement of their pistons **P1** by force received from springs beneath the valve ball **B** in each of the valves as **X3**. The pistons **72** and **73** in the control valve motor units **74** and **75** are also thus permitted to move upwardly under the influence of fluid received through the conduits **49** and **76** to exhaust any fluid in these units into the conduits **57** and **58**.

When the core **15** is rotated counterclockwise, as viewed in Figures 3 to 6, the core passages **43** and **44** do not change their status of connection. In Figure 5 it can be seen that the passage **43** will remain sealed at its ends by the body of the sleeve **14**, whereas, in Figure 6 it can be seen that the passage **44** will remain in registry with the ports **26** and **27**. Therefore the fluid motor means consisting of the fluid motor units **53**, **56** and **75**, connected with the passage **57**, will remain connected with the exhaust. Valves **X3** and **51** will remain closed and the control valve **67**—**69** will remain open. Such counterclockwise rotation of the core **15** will, however, change the connecting status of the core channels **41** and **42** comprising part of a settable valve means which controls the fluid motor means consisting of the fluid motor units **55**, **54** and **74**. In Figure 3 it can be seen that said counterclockwise rotation of the core **15** will carry the ends of the channel **41** into seating relation with the body **14** and terminate the exhaust condition for the motor units **55**, **54** and **74**. Such counterclockwise rotation of the core, as seen in Figure 4, will establish the core channel **42** in communicative relation with the ports at its opposite ends and hence with the conduits **49** and **58**. Thereupon, fluid from the source will reach the conduit **58** through the conduit **49** and will force the pistons of the motors **55**, **54** and **74** downwardly to concurrently open the valves **X3** and **X5** and close the control valve **68**—**71**.

This closing of the control valve **68**—**71** blocks escape of the fluid from the fluid receiving passage **65**, wherefore, this fluid builds up sufficient pressure beneath the by-pass valve member **62** in the chamber **79** to seat this valve member at **61**. In this manner the source **P** of actuating fluid is conditioned for operation at high pressure and the fluid flowing from the source through the passage **49** enters the inlet passage **X2** where it flows past the then opened admittance valve **X5** and the check valve **X6** into the right end of the motor cylinder. Since the exhaust valve **X9**

is now open, the fluid entering the right end of the motor cylinder can force the piston 16 to the left, while the latter exhausts fluid from the left end of the cylinder past the exhaust valve X9 and into the reservoir through the passage 52. Pursuant to movement of the piston or work member to the left, the connection 47-48 between the piston rod 48 and the valve structure sleeve 14 effects rotation of this sleeve counterclockwise. After the motor M is operated an amount correlated with the amount of setting of the core 15 in the counterclockwise direction, the motor-driven sleeve 14 will reestablish its neutral position with respect to said core, replacing the sleeve and core in the relative positions illustrated in Figures 3 to 6. Thereupon the motor units 53, 54, and 74 will be reconnected with the low pressure side of this system through the core passage 41 and disconnected from the high pressure side of this system by the cutting off of this connection through the core passage 42. This changing pressure status upon the motor units 53, 54 and 74 incurs closing of the exhaust valve X8, of the admittance valve X5 and opening of the control valve 68-71, as explained above.

Should the settable valve structure core 15 be rotated clockwise from the neutral setting, illustrated in Figures 3 to 6, the connecting status of the channels 41 and 42 of the settable valve means for controlling the motor units 53, 54 and 74 will be unchanged. Channel 41 will remain communicative between the ports 17 and 18, while the channel 42 will remain sealed at its ends by the body of the sleeve 14. Said clockwise rotation of the core 15 will, however, change the communicative status of the channels 43 and 44 of the settable valve means which control the motor units 53, 54 and 75. Core channel 44 will have its connection between the ports 26 and 27 terminated so the conduit 51 is no longer communicative with the low pressure side of the system through the conduit 85. When the core channel 44 terminates its connection between the ports 26 and 27, the clockwise rotated core will place its channel 43 communicatively between the sleeve ports 24 and 25. The status then prevails in which the channel 57 is cut off from communication with the low pressure side of the system and connected with the fluid source through the conduit 49. Thereupon the motor units 53, 54 and 75 will be subjected to an increased pressure status for opening the valves X3 and 51 and closing the control valve 67-69. Such closing of the control valve 67-69 has the same effect, described above, of closing the control valve 68-71 for conditioning the source to deliver fluid at high pressure. Fluid at high pressure enters the motor inlet passage X1 from the conduit 49 and flows past the open admittance valve X3 and the check valve X4 into the left end of the motor cylinder. Pursuant to the resulting movement of the motor piston to the right, fluid displaced from the right end of the motor cylinder is exhausted past the then opened exhaust valve 51 and through the exhaust channel 52 into the reservoir. When the motor piston has moved an amount correlated with the clockwise setting of the valve core 15, the connection between the piston rod 48 and the rotatable sleeve 14 will reestablish the relative neutral position of the core and sleeve, illustrated in Figure 3, disconnecting the conduit 57 from the conduit 49 and reconnecting the conduit 57 with the reservoir to subject the fluid motor means 53-54-75 a dimin-

ished pressure status and thereby incur closing of the valves X3 and 51 and opening of the control valve 67-69.

While the fluid motor unit 15 is being subjected to the pressure fluid from the source through the conduit 57 and also through the conduit 76, the same unit pressure will be applied to the upper and lower sides of the piston 13 of this motor unit. However, since a large diameter portion 91 projects downwardly from the lower end of the piston into a chamber 92, the area at the lower end of the piston subjected to said unit pressure will be less than the corresponding area at the upper end of the piston, so that the piston is forced downwardly for firmly closing the control valve 67-69. A low pressure condition in the motor chamber 92 is assured by a drainage channel 93 which is communicative with the reservoir through the passage 84. The arrangement for and functioning of the motor unit 15 is as just described for the motor 75.

A pressure relief valve 84 is formed within the by-pass valve member 62. Said member 62 is provided with an axial bore 88 leading to a spring chamber 86 therein. Bore 85 slidably receives a headed pressure relief valve member 91 of which the head is disposed within the chamber 86 and urged upwardly by a spring 98. Should the pressure within the passage 59 become excessive, while the by-pass valve member 62 is retained upon its seat 81, this pressure acting upon the upper end of the slidably relief valve member 91 will force this member downwardly against the force of spring 98 to establish connection between the upper end portion of the bore 88 and laterally extending bores 99 to permit escape of the fluid into the by-pass passage 63. Fluid that may leak past the member 91 into the spring chamber 86 can escape into the by-pass passage 40 through a drainage passage 100.

In a modified form of control system, shown in Figure 7, for conditioning the source of fluid to operate at relatively high and low pressures, a fluid motor unit 101 is normally energized for holding the ball 102 of a by-pass valve 103 unseated and the valve opened to create the low pressure operating condition. To simplify the description of the apparatus shown in Figure 7, those parts identical with or corresponding to parts in Figure 1, have been illustrated by the same reference characters with the addition of a prime. Control valves 104 and 105 are closed during low pressure operation. When these valves are so closed, pressure is caused to build up in the fluid receiving passage 65' for forcing the piston 106 of the fluid motor 101 upwardly to hold the biased valve ball 102 unseated. Energization of the motor units 74' and 75' by the pressure of fluid received through the conduits 58' and 57' will force the pistons of these motors downwardly for unseating the balls of their associated valves 104 and 105. When either of the motors 74' and 75' is energized for opening its associated control valve, fluid can escape from the fluid receiving passage 65', lowering the pressure therein because of the restricted section 66' therein and permitting the spring 107 to seat the by-pass valve ball 102. The most significant difference in the system shown in Figure 7, and 70 that corresponding thereto in Figure 1, is the employment of the normally closed control valves 104 and 105 in a parallel arrangement, instead of the normally open control valves 67-69 and 68-71 disclosed in series. Entailed in this 75 difference of the two systems is the fluid pressure

energization of the by-pass valve control motor 101 for maintaining the by-pass valve open in the Figure 7 embodiment in contrast to the accumulation of fluid pressure in the chamber 18 of Figure 1 for closing the by-pass valve 61-62.

Having described a limited number of embodiments of the invention with the view of clearly illustrating the same, we claim:

1. In apparatus for controlling delivery of fluid from a continuous delivery source to a fluid-driven motor for operating the same, a fluid delivery passage for communication between the source and said motor, a by-pass passage communicative with said source for by-passing the fluid therefrom about the fluid delivery passage, a pressure responsive by-pass valve in control of the flow of fluid through the by-pass passage, a fluid receiving passage communicative with said source to receive fluid therefrom and having a discharge opening which is closable to cause accumulation of fluid in such fluid receiving passage and an increase in pressure of the accumulated fluid, said discharge opening being openable to allow escape of the accumulated fluid and diminution of its pressure, said by-pass valve being subjectable to the pressure of fluid in the fluid receiving passage and being operable to close the by-pass passage when subjected to the pressure of the accumulated fluid and operable to open the by-pass passage when subjected to the diminished pressure of the escaping fluid, a fluid actuated control valve for said discharge opening and operable when subjected to pressure in one range to incur closing of such opening and operable when subjected to pressure in another range to incur opening of such opening, a control passage communicative between said source and said fluid actuated valve, settable valve means connected with said control passage and settable to utilize the pressure of fluid at said source in selectively subjecting the fluid actuated control valve to pressure in said ranges, a second settable valve means which is interposed between the delivery passage and said motor and means for coordinately setting said settable valve means to subject said fluid actuated control valve to pressure in the one range to cause closing of the by-pass valve attendant to communicatively connecting the delivery passage with the motor and to subject the fluid actuated control valve to the other pressure range to cause the open condition of the by-pass valve attendant to terminating the communicative connection of the delivery passage with said motor.

2. In apparatus for controlling delivery of fluid from a continuous delivery source to a fluid-driven motor for driving the same, a fluid delivery passage for communication between the source and said motor, a by-pass passage communicative with said source for by-passing the fluid therefrom about the fluid delivery passage, a pressure responsive by-pass valve in control of the flow of fluid through the by-pass passage, a fluid receiving passage communicative with said source to receive fluid therefrom and having a discharge opening which is closable to cause accumulation of fluid in such fluid receiving passage and an increase in pressure of the accumulated fluid, said discharge opening being openable to allow escape of the accumulated fluid and diminution of its pressure, said by-pass valve being subjectable to the pressure of fluid in the fluid receiving passage and being operable to close the by-pass passage when subjected to one of the relative fluid pressures in the fluid receiving passage and operable

to open the by-pass passage when subjected to the other of said relative pressures, a fluid actuated control valve for said discharge opening and operable when subjected to pressure in one range to incur closing of such opening and operable when subjected to pressure in another range to incur opening of such opening, a control passage communicative between said source and said fluid actuated valve, settable valve means connected with said control passage and settable to utilize the pressure of fluid at said source in selectively subjecting the fluid actuated control valve to pressure in said ranges, a second settable valve means which is interposed between the delivery passage and said motor, and means for coordinately setting said settable valve means to subject said fluid actuated control valve to pressure in the range incurring the relative pressure in said receiving passage for closing of the by-pass valve attendant to communicatively connecting the delivery passage with the said motor and to subject the fluid actuated control valve to the pressure range incurring the relative pressure in said receiving passage for opening of the by-pass valve attendant to terminating the connection of the delivery passage with the said motor.

3. In apparatus for controlling delivery of actuating fluid to a fluid-actuated device from a constant delivery source conditionable for relatively high and low pressure operation and for controlling exhaust of the fluid from the device; an inlet passage communicative between said source and said device, an admittance valve in said passage and selectively closable or openable to respectively block the admittance of fluid to the device through said passage or terminate its blocking function; an outlet passage communicative with said device; an exhaust valve in said outlet passage and selectively closable or openable to respectively block the exhaust of fluid from the device through such outlet passage or terminate its blocking function, fluid motor means operable when subjected to one status of fluid pressure to incur opening of said admittance valve and while incurring conditioning of said source for high pressure delivery and operable when subjected to another status of fluid pressure to incur closing of said admittance valve while incurring conditioning of said source for low pressure operation, additional fluid motor means operable when subjected to one status of fluid pressure to incur opening of the exhaust valve and operable when subjected to another status of fluid pressure to incur closing of the exhaust valve, and settable valve means communicatively interposed between said source and each of said motor means to utilize the pressure of fluid at said source in subjecting the motor means to different fluid pressure statuses, said settable valve means being settable from a neutral position wherein each of said motor means is subjected to fluid pressure at its other status to positions selectively creating the one status of pressure subjection of said motor means.

4. In apparatus for controlling delivery of actuating fluid to a fluid-actuated device from a constant delivery source conditionable for relatively high and low pressure operation and for controlling exhaust of the fluid from the device; an inlet passage communicative between said source and said device; an admittance valve comprising a seat surrounding a section of such passage and a member normally yieldably seated in the downstream direction upon said seat for closing said passage; an outlet passage communicative with

said device; an exhaust valve comprising a seat surrounding a section of such outlet passage and a member normally yieldably seated in the downstream direction on such seat for closing the outlet passage, fluid motor means operable when subjected to one status of fluid pressure to incur unseating of the admittance valve member while incurring conditioning of said source for high pressure operation and operable when subjected to another status of fluid pressure to incur seating of said admittance valve member while incurring conditioning of said source for low pressure operation, additional fluid motor means operable when subjected to one status of fluid pressure to incur unseating of the exhaust valve member and operable when subjected to another status of fluid pressure to incur seating of the exhaust valve member, and settable valve means communicatively interposed between said source and each of said motor means to utilize the pressure of fluid at said source in subjecting the motor means to different fluid pressure statuses, said settable valve means being settable from a neutral position wherein each of said motor means is subjected to fluid pressure at its other status to positions selectively creating the one status of pressure subjection of said motor means.

5. In apparatus for controlling selective delivery of actuating fluid to different portions of a reversibly operable motor from a constant delivery source conditionable to operate at relatively high and low pressures and for controlling exhaust of the fluid from each of said motor portions coordinate with fluid delivery to the other of such portions; inlet passages communicative between said source and said motor portions, admittance valves in said inlet passages, outlet passages communicative with said motor portions, exhaust valves in said outlet passages and respectively associated with the admittance valves in the inlet passages communicating with the corresponding motor portions, fluid motor means operable when subjected to one status of fluid pressure to open one of said admittance valves concurrently with opening the exhaust valve unassociated therewith and concurrently with conditioning said source for high pressure operation, said fluid motor means being operable when subjected to another status of fluid pressure to incur closing of said one admittance valve and of its unassociated exhaust valve and resumption of low pressure operation of the fluid source, a second fluid motor means operable when subjected to one status of fluid pressure to open the other of said admittance valves concurrently with opening the other exhaust valve and conditioning said source for high pressure operation, the second fluid motor means being operable when subjected to another status of fluid pressure to incur closing of said other admittance and exhaust valves and resumption of low pressure operation of the fluid source, and settable valve means communicatively interposed between said source and each of said motor means to utilize the pressure of fluid at said source in subjecting the motor means to different fluid pressure statuses, said settable valve means being settable from a neutral position wherein each of said motor means is subjected to fluid pressure at its other status to positions selectively creating the one status of pressure subjection of said motor means.

6. In apparatus for controlling selective delivery and exhaust of actuating fluid to and from different portions of a motor to cause movement of a work member in respectively opposite directions, the delivery being from a constant delivery source conditionable to operate at relatively high and low pressures; inlet passages communicative between said source and said motor portions, admittance valves in said inlet passages, outlet passages communicative with said motor portions, exhaust valves in said outlet passages and respectively associated with the admittance valves in the inlet passages communicating with the corresponding motor portions, fluid motor means operable when subjected to one status of fluid pressure to open one of said admittance valves concurrently with opening the exhaust valve unassociated therewith and concurrently with conditioning said source for high pressure operation, said fluid motor means being operable when subjected to another status of fluid pressure to incur closing of said one admittance valve and of its unassociated exhaust valve and resumption of low pressure operation of the fluid source, a second fluid motor means operable when subjected to one status of fluid pressure to open the other of said admittance valves concurrently with opening the other exhaust valve and conditioning said source for high pressure operation, the second fluid motor means being operable when subjected to another status of fluid pressure to incur closing of said other admittance and exhaust valves and resumption of low pressure operation of the fluid source, and settable valve means communicatively interposed between said source and each of said motor means to utilize the pressure of fluid at said source in subjecting the motor means to different fluid pressure statuses, said settable valve means comprising relatively movable complementary ported members relatively disposable in a neutral position to subject each of said motor means to its said other status of fluid pressure, one of said valve members being settable in opposite directions from the neutral position to alternatively subject said motor means to their said one status of fluid pressure to incur movement of the work member in corresponding opposite directions, and said work member being operatively connected with the other of said relatively movable ported members to move the same therewith to reestablish said neutral position when the work member has moved an amount and direction correlated with the amount and direction of movement of the one valve member.

JOSEPH F. ZISKAL.
